UNITED STATES PATENT OFFICE.

CHARLES E. REID AND JOHN HEISSENBERGER, OF NEW YORK, N. Y.

MAIL-DELIVERY APPARATUS.

No. 899,903.

Specification of Letters Patent.

Patented Sept. 29, 1908.

Application filed December 27, 1906. Serial No. 349,660.

To all whom it may concern:

Be it known that we, CHARLES E. REID and JOHN HEISSENBERGER, citizens of the United States, residing at New York, in the 5 county of New York and State of New York, have invented certain new and useful Improvements in Mail-Delivery Apparatus, of which the following is a specification.

Our invention relates to improvements in 10 mail delivery apparatus, and particularly to apparatus for delivering mail to the tenants on the different floors of apartment houses or other large buildings.

The object of our invention, is the provision of a carrier or carriers for delivering 15 mail or packages to the various floors or predetermined stations in a building, the entire operation of the carriers being automatic so that no external attention is necessary to the 20 operation of the device.

Another object of our invention is the provision of a carrier which may be started at will, which will deposit its contents at certain 25 predetermined points, and which when the proper deposition of the contents has been made, will automatically return to the starting point in readiness for the next trip.

A further object of our invention, is to provide means for controlling the operation of 30 the carriers so that the carriers may be controlled either automatically or at will.

Our invention also has for its object, to provide a carrier or a series of carriers which will automatically deposit their contents 35 only at the proper points so that there shall be no mistake in the delivery of the mail to the wrong point, and to provide means for automatically starting, stopping and governing the travel of the carriers.

We aim to accomplish the above results in 40 a simple, practical and effective manner, and to these ends our invention comprises a carrier or a set of carriers, suitable power mechanism for elevating or causing the carriers to 45 travel within certain limits, automatic means for governing the travel of the carriers, and in providing the carriers with means for the automatic discharge thereof; and the invention further consists of a mail delivery apparatus embodying certain other novel features 50 of construction, combination, and arrangement of parts substantially as herein set forth.

Figure 1, is a broken front elevation of the 55 complete mail delivering apparatus arranged for use in a three story building, parts being

shown in section and the smaller details of the invention being omitted for the sake of clearness. Fig. 2, is a transverse sectional view of the carrier chute taken on line 2—2 of 60 Fig. 1. Fig. 3, is a side elevation of the view shown in Fig. 1. Fig. 4, is an enlarged sectional view of the carrier chute and one of the carrier boxes therein, the dotted lines indicating the open or discharging position of 65 the carrier box. Fig. 5, is an enlarged plan view of the carrier boxes in the chute and the means for causing the automatic discharge of the boxes, parts also broken away and shown in section. Fig. 6, is a detail view in 70 elevation to show the manner in which the carrier boxes are connected together. Fig. 7, is a diagrammatical view of the carrier boxes and the electrical means and connections for operating and controlling the same. 75

We will first describe the invention broadly and then point out the particular details of construction, and now with particular reference to Figs. 1 and 2; the numeral 1, designates the wall of a building, and 2, the various floors of the building. A chute or stack 3, of sheet metal or other suitable material extends through the floors of the building, the chute being provided with a longitudinal compartment 4, extending its full length, and 80 having oppositely-disposed guides or channel bars 5, on its interior walls. A supporting pulley 6, is journaled at the head of the chute, over which passes the rope or cable 7, which is connected to the upper one of the series of 85 boxes or carriers 8, the other side of the cable passing down through the compartment 4 in the chute, over the guiding pulleys 9, and then wound upon the drum 10. This drum is rotated through a worm gear connection 95 11, from the motor 12, the opposite end of the drum carrying a cable 13, which passes over guiding pulleys 14, and is connected to the lowermost of the series of boxes. It will thus be seen that by rotating the motor in 100 the proper direction, the boxes will be raised or lowered in the chute.

An opening 15, is formed in the front wall of the chute (preferably at the first floor in the building) to permit of the boxes being 105 examined and loaded, a door 16, is hinged to cover said opening, and a suitable index to the occupants of the building may be arranged upon the door, as shown in Fig. 1. This opening in the chute is preferably of a 110 size to admit of several of the boxes being loaded simultaneously, and smaller openings

17, are formed in the chute at each floor or station for the discharge of the mail therethrough.

The boxes or carriers for the mail or packages have a front wall or cover plate 18, which is pivoted at the upper end at 19, and a rear wall 20, which is likewise pivoted at 21, and a flap is pivoted in the upper front edge of the box for the insertion of the mail therein. The rear wall has the angular sides 22, and a link 23, connects the front and rear walls in parallelism. Pivoted to the lower end between the angular sides of the rear wall, is a false bottom 24, and secured to the rear wall and overhanging the point of pivotal connection of the false bottom, is a deflecting flange 25. A spring 26, secured in the top of the box engages the rear wall and thereby tends to hold the box in closed position. Carried on the outer face of the rear wall, is a lug 27, having an inclined lower face and a sharp upper or abutment face. Pivoted in a socket member 28, secured to the rear wall of the chute, is a depending pawl 29, which normally rests upon a spring supported abutment 30, or other elastic support, the point of the pawl when in this position being adapted to engage the lug on the rear wall of the box. The boxes are connected in series by means of the pivoted links 31, and rollers 32, carried on the sides of the boxes engage the guides on the inner walls of the chute. A tripping pawl as described is arranged in the chute at each station and the pawls of the different stations are offset from each other as clearly illustrated in Fig. 5, and the lug on the back of each box is arranged to correspond with the pawl on the floor at which it is to discharge its contents. As the boxes are elevated in the chute, the pawls engage the respective lugs on the boxes in order, and as shown in Fig. 4 in dotted lines, the pawl forces the rear wall outwardly, likewise the front wall and the false bottom, which thereby discharges the contents of the box through the opening provided for that purpose in the chute. The boxes continue upward after being emptied and the pawls fall downward to their normal position after the boxes have all passed above the pawls in the chute. The springs close the boxes as soon as they have been acted upon by the pawls.

We will now describe the means for governing the travel of the boxes, and for this purpose, we invite attention to the diagrammatical view of the connections shown in Fig. 7. Immediately inside the door for depositing the mail in the boxes, is located a switch arm 33, carrying the individual contact points 34 and 35, fed by the feed wires 36 and 37 respectively, said contact points adapted to be advanced to the stationary contacts 38 and 39, respectively. Wires 40 and 41 extend from these last-named con-

tacts to the field winding 42 of the motor, and wires 43 and 44 are fed from said contacts and terminate each in a pair of contacts 45, 45 and 46, 46, respectively, forming part of a reversing switch. The reversing switch is also provided with two additional sets of contacts 47, 47, and 48, 48, which are connected by the conductors 49 and 50, to the armature 51 of the motor. The contact points to the reversing switch may be arranged in radiating lines as shown, and a switch lever 52, centrally pivoted serves to connect the adjacent sets of points.

When mail is to be deposited in the boxes, the switch arm 33, is thrown to the right in Fig. 7, until the boxes are brought to a level with the opening in the chute. The path of the current is then as follows: through feed wires 36 and 37, contacts 34—38, 35—39, respectively, wires 40 and 41 to the field 42 of the motor, a portion of the current dividing and flowing through conductors 43 and 44, to contacts 45 and 46, over the arm of the switch lever to points 48 and 47, thence by conductors 50 and 49, through the armature 51. This causes the motor to rotate in one, say the forward direction, carrying the boxes upward. When the boxes have all been filled, the door to the opening in the chute is then closed. This door carries on its inner face the two bridging contacts 53 and 54, adapted to connect the contacts 34—38 and 35—39 respectively, so that when this door is closed, the circuit is completed, and the boxes are carried upward in the chute, and as they reach the respective pawls at the different stations, the boxes are freed of their contents. When the last box has been discharged, an arm 55, carried by the upper box, engages the lower end of the reversing switch lever and forces the same upward, thereby reversing the rotation of the motor and causing the boxes to be lowered in the chute. When the boxes are thus descending and have nearly reached the lower end of the chute, a pawl 56, carried on the side of one of the boxes, engages the angular extension 57, on the end of the switch arm and draws the switch arm out of engagement with the contacts thereby breaking the circuit, stopping the motor and allowing the boxes to come to rest in the bottom of the chute, (provided of course that the switch arm was in engagement with the contacts when the door was closed. This pawl is simply to insure of the switch arms being out of contact the next time the door is opened, and if the switch arm was not in contact when the door was closed, then the descending pawl will have no effect on it.) A spring 58 holds the pawl 56 outstanding, that when the boxes are ascending, the pawl has no effect on the switch arm.

A stop 59, carried by the cable is arranged to engage the reversing switch lever when

the boxes have reached the bottom of the chute, so that the switch is in position for the next upward movement of the boxes.

From the foregoing description taken in connection with the drawings, it will be evident that we have accomplished all the objects herein set forth, and have provided a carrier system which may be used for a great many purposes and is thoroughly reliable and efficient.

We claim:

1. A carrier system comprising carriers, a guide-way therefor, closures to the guide-way, power mechanism for the carriers, means for manually controlling the power mechanism to operate the carriers, means operated by one of the closures for starting the carriers, means for reversing the travel of the carriers and for stopping the same in their original position, and means for restoring the controlling means to the original position.

2. In a carrier system, the combination with carriers and a passage-way therefor, closures to the passage-way, electric motive power for the carriers, electrical connections including a manually operated switch and a reversing switch, bridging contacts operated by the movement of one of the closures for starting the carriers, means for operating the reversing switch when the carriers have reached one limit of travel, and means for restoring the reversing switch to the original position when the carriers have returned to their original position.

3. The combination with carriers having pivoted front, rear and bottom walls, a chute in which the carriers are adapted to travel, of selective means in the chute to engage the rear wall of certain of the carriers and cause outward, opening movement of the pivoted walls thereof.

4. The combination with a chute, of carriers therein having pivoted walls, selective means in the chute for causing discharge of the carriers, an electric motor and connections for elevating the carriers, a manually-operated controlling switch and automatically-operated reversing switch in circuit with the motor, a door to the chute, and contacts on the door to complete the circuit and cause travel of the carriers.

5. The combination with a guideway, of carriers therein, means for causing discharge of the contents of the carriers, closures to the

guideway, power mechanism for the carriers, means for manually controlling the power mechanism, means operated by one of the closures for controlling the power mechanism, means for reversing the power mechanism to stop the carriers in their original position, and means for restoring the controlling means to the original position.

6. A carrier comprising a casing having a rear open side, a rear wall pivoted at the upper end to close said open rear side and provided with angular side extensions, a pivoted front wall, links connected between the front and rear wall, a false bottom pivoted between the angular sides of the rear wall, a depending flange on the rear wall overhanging the pivotal connection of the false bottom, and a spring engaging the rear wall to hold the parts normally closed.

7. A series of carriers each consisting of a frame member open in front and rear, a rear wall pivoted in each carrier to form a closure to the open rear side thereof, a front wall pivoted to each carrier, means connecting the front and rear walls together, a false bottom in connection with the rear wall, means for holding the walls normally closed, and links connecting the carriers in series.

8. In combination with a chute, socket members carried by the rear wall thereof, pawls pivotally mounted in said socket members, cushion supports for the free ends of the pawls, and carriers contained in the chute to be acted upon by the pawls.

9. A carrier system comprising in combination, carrier frames open in front and rear, a rear wall pivoted to form a closure to said open rear side of each carrier, front pivoted walls to the carriers, means connecting the front and rear walls in parallelism, false bottoms pivoted to the rear walls of the carriers, means for holding the walls of the carriers normally closed, means connecting the carriers in series, a guideway for the carriers, means for moving the carriers in the guideway, and means for causing outward opening movement of the carriers.

In testimony whereof we affix our signatures in presence of two witnesses.

CHARLES E. REID.
JOHN HEISSENBERGER.
